BOYD M. JOHNSON, OF METUCHEN, NEW JERSEY, ASSIGNOR TO THE CARBORUNDUM COMPANY, OF NIAGARA FALLS, NEW YORK, A CORPORATION OF PENNSYLVANIA

CONTINUOUS CONVEYER FURNACE

Application filed May 22, 1929. Serial No. 365,206.

My invention relates particularly to improvements in continuous conveyer furnaces and driers where it is desired to transport articles continuously at a slow rate through long drying and heating chambers. It has been found in using such furnaces that so much heat may be lost by radiation, convection and conduction through the ends of the furnaces that the desired temperature cannot be maintained at the center. The temperature that can be maintained in the central portion of the heating furnace where the ware is fired has been found to be also much influenced by the number and size of articles that are being treated.

I have found means to cut down effectively the losses referred to above. These means are illustrated by the accompanying drawings, which are more or less schematic, and in which:

Figure 1 is an elevation giving an end view of a furnace having adjustable doors through which a basket laden with ware is passing;

Figure 2 is a diagrammatic plan view showing the general arrangement of a continuous conveyer furnace embodying my invention;

Figure 3 is an elevation showing a removable shield;

Figure 4 is an end elevation of a tunnel kiln or furnace, showing another shield arrangement and its relation to the tunnel, there being three shields one of which is removable and the others fixed;

Figure 5 is a view generally similar to Fig. 4 in which all the shields are removable;

Figure 6 is a view similar to Fig. 4 in which the ware under treatment is indicated by dotted lines;

Figure 7 is a diagrammatic plan view of a modified continuous conveyer furnace in which the radiation losses from the combustion chamber are reduced by turning the ends of the kiln at right angles to the central portion;

Figure 8 is a diagrammatic plan view of another modification in which a drying chamber is indicated as connected with a continuous conveyer furnace having its ends bent in opposite directions;

Figure 9 represents a modification of the type indicated in Fig. 8 in which the drying chamber and combustion chamber are separated;

Figure 10 is still another diagrammatic plan view of a combined continuous conveyer furnace and drier in which the ware is carried through the furnace in a prolonged tortuous path;

Figure 11 is a vertical section of a further modification in which the furnace and drying chamber are in vertically disposed relation; and

Figure 12 is a vertical section on the line 12-12 of Fig. 11 in which the hangers and loads are indicated diagrammatically.

Referring to the drawings in more detail, 2 is a combustion chamber through which the ware passes in the direction of the arrow A after being preheated in the chamber 3, which the ware enters usually after a preliminary drying in chambers such as are indicated in Figures 8 and 9 at 22 and 22' respectively. Opposite the preheating chamber is an exit or cooling chamber 3'. The waste gases move as indicated by the arrow B in a direction opposite to that of the ware. The ware is carried through the tunnel kiln by means of a conveyer 4, from which is suspended a basket 5 by means of a hanger 6. The hanger 6 passes through a slot 7 in the roof of the furnace. The hanger 6 carries a sealing plate 9 which rides on pipes 10 which may be water-cooled. A guide member 13 may be used to aid in keeping the hanger 6 in the middle of the slot.

The shields 8 play an important part in the economy of the furnace operations since they reflect a portion of the radiation toward the hotter part of the furnace. They tend to prevent loss of the heat by convection as well as by radiation. The size of the openings through which the travelling shields and ware pass may be adjusted by means of the adjustable doors 11. These shields may be attached or removed readily by having the shields slotted as indicated in Figure 3. The shields may be made up in parts as shown in Figure 4 where 8' is a portion of a shield permanently attached to the basket and 8'' is

a removable portion of the shield. In this case the ware 12 itself acts as a radiation shield for a portion of the cross-sectional area of the continuous conveyer furnace. In Figure 5 a plurality of removable shields 8" are shown. There is no permanent shield in this case. In Figure 6 the ware is shown as mounted in two stages, a permanent shield 8 being used.

As shown in Fig. 2, the shields are preferably so positioned that there is at all times at least one shield in the preheating chamber 3 and in the exit chamber 3'. This assures of there being no direct open channel along the path of travel of the ware from either end of the firing chamber directly to the atmosphere.

Another method of cutting down loss by radiation is illustrated in Figures 7, 8, 9 and 10. As shown in Figure 7 the end 23 of the preliminary heating chamber and the end 24 of the cooling chamber are shown as turned at right angles to the combustion chamber 2'. This arrangement gives a continuous conveyer furnace in which the interior conditions more closely resemble those of a black body than is the case in a straight tunnel kiln. The expression "black body" is used here in the sense employed in treatises on radiation. Briefly, a "black body" is one whose emissivity is 100 percent. This condition is reached practically in the case of a nearly enclosed muffle in which the temperature of the inner lining is measured through an opening which is small as compared with the total area of the incandescent lining.

In Figure 8 a continuous conveyer furnace is shown in which the ends 23' and 24' are turned at right angles to the combustion chamber 2" and in opposite directions. In this case the preliminary heating section of the furnace is continuous with the drying chamber 22. In Figure 9 the ends 23" and 24" of the continuous conveyer furnace are shown as turned in the same direction at right angles to the combustion chamber. The drying chamber is in this case not continuous with the furnace. In Figure 10 the drying chamber 22" is sufficiently extended in two horizontal dimensions so that the ware can be carried in a long tortuous path through the drying chamber.

In Figures 11 and 12 the drying and heating chambers are vertically disposed with respect to each other and the slot is formed in an intermediate partition separating the heating chamber and drying chamber. The conveyers in this case comprise an endless chain 14 to which is welded or otherwise secured a plurality of shafts 15 on which the wheels 16 are free to turn. The baskets 5 are also loosely mounted on the shafts 15. The chain 14 is driven continuously by the sprocket wheel 17. The latter is driven by a shaft 19, which is turned by outside means connected to a gear 20 keyed on the shaft 19. Shields may be carried on the baskets in this

modification as well as in the other modifications. Since the end wall 21 contains no doors whatever the heat is economized by this arrangement as well as by travelling shields.

The advantages of my invention in reducing radiation losses in continuous conveyer furnaces will be apparent from the foregoing description. It has been found by trial that the losses by radiation and convection in a straight conveyer furnace with slotted roof are ordinarily so great as to prevent the proper heating of the ware. As compared with furnaces having stationary charges large amounts of heat are carried away by the ware. There are ordinarily extensive radiation losses from the main heating chamber to the extended sections which are used for preheating the ware before the firing operation and for cooling it after the firing operation. There are also ordinarily serious convection losses through the slotted roof and through the end doors. I reduce the losses through the slotted roof by means of seals as indicated in Figure 1. The convection losses through the end doors are reduced by the plurality of shields used in connection with end doors of adjustable size.

The bending of the ends of the continuous conveyer furnace, as indicated in Figures 7, 8, 9 and 10 at both ends and at one end in the modification shown in Figures 11 and 12, contributes to compactness of design. Moreover loss by radiation and by convection is reduced. The radiation from the firing chamber is subjected in the extensions to a series of multiple reflections which gives conditions more resembling that of an enclosed muffle than is possible with the ordinary straight continuous conveyer furnace.

While the ends of the furnace are shown as bent at right angles to the main body of the furnace, I do not desire to limit myself to this particular angle or to the particular L-shaped extensions shown in the drawings. Either one or both ends of the furnace may be bent. Furnaces of this kind are adapted for the firing of enameled ware and the burning or heat treating of various ceramic or other articles.

The general object of my invention is to produce a greater uniformity of temperature in continuous conveyer furnaces where articles are transported continuously or intermittently for successive heat treatments.

I claim:

1. A continuous furnace into which articles to be fired are continuously fed and from which articles which have been fired are continuously discharged, having an endless conveyer therealong for transporting successive articles to be heat treated therethrough, and shields supported by the conveyer traveling with the ware and arranged transversely to the direction of travel of the ware, to retard the transmission of radiation through the

- ends of the furnace and providing the only closure for the passageway to the furnace.
2. In combination with a furnace for the successive heat treatment of articles of manufacture, a conveyer comprising a driven member situated above the furnace, a slot in the roof of the furnace, means extending from the driven member through the slot to support the ware under treatment, and a series of spaced transverse vertical shields and horizontal shields closing the slotted roof attached to said supporting means to reduce radiation and convection losses within the furnace.
3. A furnace for the successive heat treatment of articles of manufacture comprising a central firing chamber and a substantially L-shaped extension through which the ware is carried at each end of said firing chamber providing separated terminal portions for the furnace and whereby radiation from the firing chamber toward the inlet and outlet is subjected to multiple reflections and substantially retained within the furnace.
4. A furnace for successive heat treatments of articles of manufacture comprising an L-shaped preheating section forming a charging terminal for the furnace, a firing chamber connected at one end to the inner leg of said L-shaped section, and an L-shaped cooling section in which the inner leg of the L is connected to the opposite end of the firing chamber and forming a discharging terminal located at the opposite end of the furnace structure and spaced from the charging terminal.
5. A furnace for the continuous heat treatment of articles of manufacture comprising a central firing chamber, two L-shaped extensions spaced apart from each other and continuous with said firing chamber, one of which is at one end of the firing chamber for preheating the articles and the other of which is at the other end of the firing chamber for gradually cooling the articles after the firing, and means for carrying ware through the chamber and its said extensions.
6. A furnace for the heat treatment of articles of manufacture comprising a central firing section, an L-shaped preheating section connected with one end of said firing section, an L-shaped cooling section connected to the opposite end of said firing section, a slot in the roof of each of said sections, a continuous conveyer above said furnace, means connected to the conveyer and extending through said slot for transporting the articles under heat treatment, and shields carried by said means to reduce the radiation and convection losses from said furnace.
7. A furnace for the successive heat treatment of articles of manufacture comprising a central firing chamber and extensions at each end of said firing chamber continuous therewith but having portions at each end thereof

which are continuations of the furnace and through which the ware passes, said extensions being bent away from the general direction of the central portion of the furnace whereby the articles are carried in a devious path through the furnace and the radiation losses from the furnace are reduced, said extensions providing separated terminals at opposite ends of the firing chamber.

8. An open end furnace in which both ends are turned at an angle to the main body of the furnace, whereby radiation from the central combustion chamber toward the ends is subjected to multiple reflections and hence the temperature of the central combustion chamber is substantially maintained at the value it would have if the ends of the furnace were in alignment with the central combustion chamber and enclosed, and a continuous conveyer for transporting articles to be heated through the furnace, said conveyer being arranged to carry the ware through the turned ends of the furnace as well as through the main body thereof, the turned end portions providing separated charging and discharging terminals.

9. In combination with open end furnaces, a continuous conveyer for transporting articles to be treated through the furnace, a plurality of traveling shields carried on the conveyer along with the articles through one end portion, thence through the combustion chamber and finally through the other end portion, the radiation from the central combustion chamber towards the ends being reflected away from the ends of the furnace by the shields, whereby the temperature of the combustion chamber is maintained at substantially the value it would have if kept enclosed.

10. In open end furnaces, a continuous conveyer for transporting articles to be treated through the furnace, a plurality of traveling shields on the conveyer which are carried along with the articles through one end portion thence through the combustion chamber comprising the central portion of the furnace and finally through the other end portion, the ends of the furnace being offset with respect to the central portion of the furnace, the shields and offset ends cooperating to reduce the radiation from the central combustion chamber toward the ends and to reflect such radiation away from the ends whereby the temperature of the combustion chamber is maintained at substantially the value it would have if enclosed.

11. The furnace in claim 10 in which permanent and adjustable end doors are used whereby the shields are of substantially the same size as the end openings through which they pass.

12. The method of reducing heat losses in a furnace for firing ware and wherein a continuously moving conveyor is employed

- which comprises placing, at the time of loading with ware, removable screens on the conveyer carrying ware therethrough, said screens being so selected as to decrease heat transfer lengthwise of the furnace.
13. A continuous furnace having an endless conveyer thereover for transporting successive articles to be heat treated through the furnace, shields travelling with the ware and arranged transversely to the direction of travel of the ware for retarding the transmission of radiant heat lengthwise of the furnace, and adjustable shields at each end of the furnace which may be adjusted to complement the shields which travel with the ware, whereby substantially the entire cross sectional area of the furnace is blocked against loss of heat by radiation lengthwise of the furnace.
14. A furnace for the heat treatment of articles of manufacture comprising a central firing chamber having extensions at each end thereof forming separated terminal portions which are continuous therewith but offset with respect thereto, said extensions forming continuations of the furnace, a continuous conveyer for carrying articles through the furnace, including the extensions, and transverse shields on the conveyer for retarding the transmission of heat by radiation in the direction of travel of the conveyer.
15. The method of operating a continuous furnace for the burning of ware wherein the ware is carried on supporting elements hung from a continuous conveyer which comprises attaching shields to the conveyer at intervals according to the character of the ware being enameled.
16. A tunnel kiln designed for continuous operation over prolonged periods in which the ware is transported by means of an overhead conveyer which carries the ware by means of hangers which project through a slotted roof in the furnace, said tunnel having its ends turned at right angles to the firing chamber and the conveyer track being similarly deflected so that ware can be carried through the furnace without the usual interruption of its progress at the inlet and outlet respectively.
17. A tunnel kiln designed for continuous operation over prolonged periods having a slotted roof and overhead conveyer, means extending from said conveyer through said slot for supporting ware under treatment, and light adjustable shields carried by said supporting means and shaped to substantially prevent loss by radiation through the inlet and through the outlet of the tunnel.

In testimony whereof I have hereunto set
my hand.

BOYD M. JOHNSON.
